(57) **CLAIM**

The ornamental design for a package for a foot care product, as shown and described.

DESCRIPTION

FIG. 1 is a front perspective view of a package for a foot care product in accordance with the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof;

FIG. 9 is a front perspective view of a second embodiment of a package for a foot care product in accordance with the present invention;

FIG. 10 is a front elevational view thereof;

FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof;

FIG. 16 is a rear perspective view thereof;

FIG. 17 is a front perspective view of a third embodiment of a package for a foot care product in accordance with the present invention;

FIG. 18 is a front elevational view thereof;

FIG. 19 is a rear elevational view thereof;

FIG. 20 is a left side elevational view thereof;

FIG. 21 is a right side elevational view thereof;

FIG. 22 is a top plan view thereof;

FIG. 23 is a bottom plan view thereof;

FIG. 24 is a rear perspective view thereof; and,

FIG. 25 is a second front perspective view of FIG. 1, shown in an environmental state.

The broken lines shown for a package for a foot care product represent unclaimed subject matter and form no part of the claimed design.
